(57) **CLAIM**

The ornamental design for a dosage form, as shown and described.

DESCRIPTION

FIG. 1 is a first perspective view of a dosage form; FIG. 2 is a top plan view of the dosage form of FIG. 1; FIG. 3 is a bottom plan view of the dosage form of FIG. 1; FIG. 4 is a top plan view of the dosage form of FIG. 1; FIG. 5 is a side view, in elevation, of a first side of the dosage form of FIG. 1;

FIG. 6 is a side view, in elevation, of a second side of the dosage form of FIG. 1;

FIG. 7 is a side view, in elevation, of a third side of dosage form of FIG. 1; and,

FIG. 8 is a second perspective view of the dosage form of FIG. 1.

The broken lines are included for the purpose of illustrating portions of the dosage form and form no part of the claimed design.

1 Claim, 5 Drawing Sheets
